(57) **CLAIM**

I claim the ornamental design for a phone case, as shown and described.

DESCRIPTION

FIG. 1 is a rear perspective view of a phone case, showing my new design, shown in an open position;

FIG. 2 is a rear elevational view thereof, shown in an open position;

FIG. 3 is a front elevational view, shown in a closed position;

FIG. 4 is rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depicting a hang strap represent portions of the phone case that form no part of the claimed design. The broken lines shown on the surfaces of the wallet portion of the phone case represent stitching that forms a part of the claimed design.
